Attorney

UNITED STATES PATENT OFFICE.

ROBERT MORSE WITHYCOMBE, OF SYDNEY, NEW SOUTH WALES, AUSTRALIA.

TOOTHBRUSH.

Application filed June 6, 1922. Serial No. 568,284.

REISSUED

To all whom it may concern:

Be it known that I, ROBERT MORSE WITHYCOMBE, a subject of the King of Great Britain, residing at Sydney, in the State of New South Wales, Commonwealth of Australia, have invented certain new and useful Improvements in Toothbrushes, of which the following is a specification.

This invention relates to brushes for 10 cleaning the teeth or massaging the gums in which the frictional surface is composed of soft rubber.

The object of the present invention is to provide a brush which can be constructed 15 at comparatively low cost and in which the frictional surface is readily removable.

According to the invention, I take a narrow strip of soft rubber and divide it into serrations or filaments for a portion of its 20 width. The strip is then wound on a former, preferably of elongated shape, under tension, the parallel or concentric layers or windings, but not the filaments, being suitably cemented or secured together.

25 The wound strip is then removed, the serrations or filaments forming the frictional surface. The handle or holder has a stem at the end of which is an extension having integral or secured thereon, a rigid base or 30 core piece, approximately corresponding in shape to the said former on which base the wound strip or frictional surface is sprung so as to be held thereon.

I now refer to the accompanying sheet of 35 drawings which illustrate one form of my invention,

Figure 1 being a perspective view of a tooth brush made in accordance with my invention.

40 Figure 2 is a similar view of a portion of a handle having core pieces on an extension thereof.

Figure 3 represents in plan view a fragment of rubber strip divided into filaments for a portion of its width.

45 Figure 4 is an inverted plan of the wound strip after removal from a former, while

Figure 5 is a section on line A—B, Figure 4.

The same numerals indicate the same or 50 corresponding parts.

The strip of rubber 7 is cut for a portion of its width into a series of filaments or serrations 8 and the strip wound under tension on a suitable former into an elongated shape, 55 the adjacent folds or windings being cemented or secured together. Midway in the space 9 left on removal of the former I prefer to insert a spacer piece 10 and secure it by an aluminium or other metal fastening 60 11. The wound strip is then sprung onto the pieces 12, 12, rigid or integral with the extension 13 of the handle 14 so that the filaments form the frictional surfaces of the brush. The wound strip is readily removable for cleaning purposes or for replacing with a new wound strip.

65 I claim:—

1. A tooth or massage brush comprising a handle, having a pair of spaced lugs thereon, 70 a strip of rubber serrated on one edge and wound upon itself under tension and sprung upon said lugs.

2. A tooth or massage brush comprising a handle, having a pair of spaced lugs thereon, 75 a strip of rubber serrated on one edge and wound upon itself under tension and sprung upon said lugs, a spacer piece centrally of said rubber, and a fastening holding said spacer piece in place.

80 In testimony whereof I have hereunto set my hand.

ROBERT MORSE WITHYCOMBE.
